CLAIM

The ornamental design for an electrical connector, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a right-front-top perspective view of the electrical connector showing my new design;

FIG. 2 is a front view thereof;

FIG. 3 is a top view thereof;

FIG. 4 is a bottom view thereof;

FIG. 5 is a rear view thereof;

FIG. 6 is a left view thereof; and,

FIG. 7 is a right view thereof.

The broken lines in the drawings illustrate portions of the electrical connector that form no part of the claimed design. The surfaces shown without shading or color, including those bounded by solid lines, form not part of the claimed design.
